COMPOSITE SET.

Application filed December 18, 1926. Serial No. 155,728.

This invention relates to multiplex signaling systems and more particularly to improvements in selective arrangements usually associated with the terminal facilities of the lines of such systems to prevent the different currents utilized from interfering with each other.

In a signaling system in which both telephone and telegraph currents are transmitted over the line circuits thereof it has been the practice to associate with the terminal facilities of such line circuits a device known as a composite set whereby the incoming telegraph and telephone currents may be separated and diverted to their respective circuits without interference with each other. The composite set, furthermore, functions to prevent the outgoing telegraph currents from entering the telephone path at the terminal facilities and vice versa. Heretofore, composite sets have separated the telephone and telegraph channels by means of frequency selectivity. The improved composite set of this invention not only makes use of frequency discrimination or selectivity to separate the incoming telephone and telegraph channels, but embodies certain novel features and principles with respect to the prevention of interference between the different types of currents originating in the different telephone and telegraph branches at the terminal facilities. By satisfying certain impedance relations in the composite set of this invention, it is possible to obtain a conjugate relationship between the telephone and telegraph branch so that interfering currents from either of these cannot enter the other regardless of frequency discrimination. Furthermore, by making the impedance of both the telegraph and telephone terminal apparatus substantially equal to a common pure resistance, the impedance of the two, as seen through the composite set, to the line, also is substantially equal to a pure resistance at all frequencies. Also the impedance of the line to the telephone and telegraph, as seen through the composite set, may be made pure resistance, line impedance, or other desired impedance. This will tend to improve the transmission characteristics of the systems by obviating echoes, reflections, and reflection losses. Further features or objects of the invention will appear more fully from the detailed description hereinafter given.

The invention may be more fully understood from the following description, together with the accompanying drawing in the Figures 1 to 8 of which the invention is illustrated. Figs. 1, 2, 4 and 5 illustrate schematically, certain principles involved in the invention. In Figs. 3 and 6, the invention is shown in schematic form. Fig. 7 shows a practical embodiment of the invention, and Fig. 8 a modification thereof.

One of the principles utilized in the composite set of this invention is illustrated in Fig. 1, in which the telegraph and telephone branches are shown tentatively as connected to the opposite sides of a Wheatstone bridge composed of the equal resistances r_1 , r_2 , r_3 and r_4 . According to the well known principles of the Wheatstone bridge current coming in over the telegraph branch will not be transmitted out over the telephone branch as the points P_1 and P_1' are of equal potential. Likewise, current from the telephone branch will not be transmitted out over the telegraph branch as the latter would be connected to the equi-potential points P_2 and P_2' . In other words, a conjugate relationship is established between the telephone and telegraph branch so that interfering currents from either of these branches cannot enter the other, even without frequency discrimination. The line circuit is shown schematically as associated with one of the arms of the bridge.

In Fig. 2, a capacity C is substituted for the resistance arm r_2 of Fig. 1 and the resistance arm r_3 is changed into an inductance L . By proper adjustments of the constants of the arms of the Wheatstone bridge, a conjugate relationship may still be established between the telegraph and telephone branches so that interfering currents from either of these cannot enter the other regardless of frequency discrimination. Because of the capacity C , the low frequency currents coming in from the telegraph branch will not take the path Cr_4 but will take the path r_1L . On the other hand, the high frequency currents from the telephone branch, due to the inductance L , will not take the path Lr_4 but will follow the path r_1C . Accordingly, by utilizing an inductance and a capacity as arms of the Wheatstone bridge and connecting the telephone and telegraph branches thereto, as shown, we find that currents from both branches will be transmitted through the

arm r_1 . Accordingly, the line circuit will be associated with this arm r_1 in the manner to be pointed out hereinafter.

The composite set of the invention is shown 5 in schematic form in the arrangements of Fig. 3. The arrangement and proportionment of the elements of Fig. 3 will be more apparent from a discussion of Figs. 4 and 5.

In Fig. 4 is shown an arrangement of impedances which has the following properties:

(1) Opposite resistances are conjugate.
(2) The impedance connected to any one of the four resistances is a pure resistance equal to R . These facts are made more obvious if the figure is redrawn to an equivalent form, as shown in Fig. 5, in which the same impedances are shown in the form of a balanced Wheatstone bridge, which is readily familiar and is known to have the two properties above stated. This figure also permits us to state by inspection what the necessary relations must be in order that the network, as shown in Fig. 4, should have these properties.

The equation

$$R^2 = \frac{L}{C}$$

expresses the necessary and sufficient condition.

Accordingly, if we now substitute the telephone and telegraph terminal circuits and apparatus for the right and left resistance elements R of Fig. 4 and connect the line circuit in place of the lower resistance and make the upper resistance a balancing network, it will be apparent that we will have the composite set shown schematically in Fig. 3 and this composite set will have the above referred to properties. Accordingly, by thus satisfying certain impedance relations and by connecting the telegraph and telephone branches, as shown, a conjugate relationship is established between these branches so that interfering currents from either of these branches cannot enter the other regardless of frequency discrimination. It is pointed out that energy from the member marked "Line circuit" in Fig. 3 is not equally divided between the telephone and telegraph branches but that the ratio of division is a function of frequency. At a frequency determined by the relation

$$\omega^2 = \frac{1}{LC}$$

the energy divides equally between these two members. At higher frequencies, the major part of the energy is transmitted to the telephone branch and only a small portion to the telegraph branch. At lower frequencies the opposite is true. It will be obvious, therefore, that such a composite set would combine the properties of frequency discrimination which is employed in present standard composite sets with the property of balance be-

tween the line and network or in other words, conjugacy between the telephone and telegraph branches.

It is pointed out that it is also desirable to make the impedance of both the telegraph and telephone terminal apparatus substantially equal to a common pure resistance. Under such conditions, the impedance of the two as seen through the composite set from the line equals a pure resistance at all frequencies. This will tend to obviate echoes, reflections and reflection loss and materially improve transmission. It may be preferable, however, to make the impedance facing the telephone or telegraph branches, or both, an impedance easy to simulate by means of a simple network,—perhaps pure resistance or line impedance. It may, therefore, be desirable to make the r_3 and r_4 members of the bridge impedance different from pure inductance and capacity, respectively, and r_4 member different from pure resistance or line impedance. This, obviously, may be done if the condition for conjugacy is maintained such as $r_2 r_3 = r_1 r_4$. Frequency discrimination 90 will be obtained if r_3 be an impedance high at telegraph frequencies and low at telephone frequencies and r_2 the reverse.

In carrying the design from the schematic form shown in Fig. 3 to a form, which is practically applicable, certain facts have to be considered. In the first place, the line met with in practice is balanced to ground. In the second place, it is not permissible to establish this balance by means of a transformer because it is necessary to transmit direct current. Some care must also be taken so that the number of connections between the composite set and the circuits which it connects should not be greater than necessary.

In Fig. 6 is shown an arrangement which applies one balancing network BN to each of the two line wires. This gives two sets of places for the telephone and telegraph to be connected. The telegraph case can be reduced to a single one immediately by making the connection indicated in the dotted line. The two telephone branches can be combined in a similar manner by the use of a transformer. The corresponding arrangement is shown in Fig. 7, which is arranged in a more usual manner and includes connections for a phantom circuit.

The arrangement shown in Fig. 7 is not as good or desirable in respect to the matter of deriving the phantom circuit, shown as the connection Ph, because the phantom telephone circuit does not derive the benefit of the balance discrimination. The arrangement shown in Fig. 8 is more satisfactory in this respect in that the phantom circuit is put on the same basis as the side circuits. The apparatus shown above the dotted line in Figs. 7 and 8 is external to the composite set proper, but should be grouped with the ap-

paratus below the dotted line for the sake of simplifying the wiring. The apparatus above the dotted line is made up of three transformers which have been designated I, II and III. I and II are the side circuit transformers and III is the phantom circuit transformer. The poling of the various windings is indicated by the numerals which are so arranged that current flowing from an odd to an even terminal produces magnetism of a given sign. The cross-fire among the various telegraph circuits seems to be taken care of, particularly if the neutral point is grounded, as indicated by the dotted connection in Fig. 8.

While the invention has been disclosed as embodied in certain specific arrangements which are deemed desirable, it is understood that it is capable of embodiment in many other and widely varied forms without departing from the spirit of the invention as defined by the appended claims.

What is claimed is:

1. A Wheatstone bridge substantially balanced for all frequencies having one set of opposite arms comprising a line circuit and a balancing network and another set of opposite arms comprising an inductance and a capacity, respectively, a telegraph circuit connected to the junction point of said line circuit and said capacity and to the junction point of said inductance and said balancing network, and a telephone circuit connected to the junction point of said line circuit and said inductance and the junction point of said balancing network and said capacity.

2. A line circuit, a balancing network, an inductance, a capacity, the impedances of said elements being so adjusted and said elements being so arranged as to form a Wheatstone bridge substantially balanced for all frequencies, and a telephone circuit and a telegraph circuit so associated with said elements as to be in conjugate relationship with each other.

3. A Wheatstone bridge substantially balanced at all frequencies having one set of opposite arms comprising a line circuit and a balancing network and another set of opposite arms comprising an inductance and a capacity, and signaling circuits of different types connected to the opposite junction points of the arms of said bridge.

4. A transmission line and a composite set associated therewith, said composite set comprising a telephone circuit and a telegraph circuit so arranged as to be in conjugate relationship to each other and having the constants of said circuits so adjusted that the impedances presented to said circuits will each be substantially equal to a common pure resistance.

5. A balanced Wheatstone bridge having one set of opposite arms comprising a line circuit and a balancing network and another

set of opposite arms comprising an inductance and a capacity, a telegraph circuit connected to the junction point of said line circuit and said capacity and to the junction point of said inductance and said balancing network, and a telephone circuit connected to the junction point of said line circuit and said inductance and the junction point of said balancing network and said capacity, the constants of said telephone and telegraph circuits being so adjusted that the impedances of said circuits will each be substantially equal to a common pure resistance.

6. A balanced Wheatstone bridge having one set of opposite arms comprising a line circuit and a balancing network and another set of opposite arms, one of which comprises an impedance much larger for telephone than for telegraph currents, and the other of which comprises an impedance much larger for telegraph than for telephone currents, a telegraph circuit connected to the junction point of said line circuit and the last mentioned one of said second set of opposite arms, and to the junction point of said network and the first mentioned one of said second set of opposite arms, and a telephone circuit connected to the junction point of said line circuit and the first mentioned one of said second set of opposite arms and to the junction point of said network and the second mentioned one of said second set of opposite arms.

7. A balanced Wheatstone bridge having one set of opposite arms comprising a line circuit and a balancing network and another set of opposite arms one of which comprises an impedance much larger for telephone than for telegraph currents and the other of which comprises an impedance much larger for telegraph than for telephone currents, a telegraph circuit connected to the junction point of said line circuit and the last mentioned one of said second set of opposite arms and to the junction point of said network and the first mentioned one of said second set of opposite arms, and a telephone circuit connected to the junction point of said line circuit and the first mentioned one of said second set of opposite arms and to the junction point of said network and the second mentioned one of said second set of opposite arms.

8. A balanced Wheatstone bridge having one set of opposite arms comprising a line circuit and a balancing network and another set of opposite arms one of which comprises an impedance much larger for telephone than for telegraph currents and the other of which comprises an impedance much larger for telegraph than for telephone currents, a tele-

graph circuit connected to the junction point of said line circuit and the last mentioned one of said second set of opposite arms and to the junction point of said network and the first mentioned one of said second set of opposite arms, and a telephone circuit connected to the junction point of said line circuit and the first mentioned one of said second set of opposite arms and to the junction point of said network and the second mentioned one of said second set of opposite arms, the con-

stants of the arms of said bridge being so adjusted that as seen from either of said telephone circuit or said telegraph circuit the impedance of the bridge will be substantially equal to the line impedance within the working frequency range. 15

In testimony whereof, I have signed my name to this specification, this 17th day of December, 1926.

HARRY NYQUIST.
